UNITED STATES PATENT OFFICE.

MARTIN R. KENYON, OF PROVIDENCE, RHODE ISLAND.

IMPROVEMENT IN LAMP-CHIMNEY CLEANERS.

Specification forming part of Letters Patent No. 35,939, dated July 22, 1862.

To all whom it may concern:

Be it known that I, MARTIN R. KENYON, of Providence, in the county of Providence and State of Rhode Island, have invented a new and Improved Lamp-Chimney Cleaner for Cleaning and Polishing the Interior Surface of Glass Lamp-Chimneys; and I do hereby declare that the following is a full, clear, and exact description of the same, reference being had to the accompanying drawings, making part of this specification, in which—

Figure 1 is a full-sized representation of the said cleaner. Fig. 2 represents the cleaner within a glass lamp-chimney, showing the manner in which the elastic fingers I I I, &c., adapt themselves to the contour of the chimney. Figs. 3, 4, 5, 6, and 7 are details, which are referred to in the course of the description.

Similar letters of reference indicate corresponding parts in all the figures.

My invention consists, first, in the use of a series of elastic fingers, covered with worsted, cotton yarn, chamois-skin, or other suitable material, and so arranged upon a suitable stem or rod that they will yield in a direction parallel with such stem or rod, and thereby exert a yielding pressure against the interior surface of a lamp-chimney and conform to the shape thereof; second, in the peculiar arrangement of two sets of such fingers, as shown in Fig. 1—that is to say, one end of each finger being fixed to the stem and the other being loose, the loose ends of each set extending toward the fixed ends of the other set; third, in combination with two sets of elastic fingers so arranged, two sliding disks arranged with a spiral spring encircling the stem in such a manner as to press the said disks against the fixed ends of the elastic fingers, and thereby spread the loose ends asunder and give additional elasticity to the said fingers.

To enable others skilled in the art to make and use my invention, I will proceed to describe the same.

In Fig. 1, I I I, &c., are the elastic fingers, which consist of flat springs *i*, of steel or rolled brass, as shown in Figs. 3 and 5, covered with worsted or cotton yarn wound thereon, or with a sheath of chamois-skin. If the said springs *i* are first covered with cotton braid, after the manner of covering the spring-wire of hoop-skirts, the yarn or leather may be fixed more

securely thereon. The elastic fingers are firmly fixed at one end to the stem *h* by means of the collars *m* *n*, in each of which is formed a triangular hole, between the flat sides of which and a triangular shape formed upon each end of the stem *h* the ends of the springs *i* are held, as shown in Figs. 3, 5, and 6, the stem being necessarily formed in two pieces to admit of this construction, and being united at *a* in the long collar *m*, Fig. 6. There are two sets of three (3) fingers each, one set being fixed in the collar *n* and the other in the collar *m*, and they are so arranged upon the stem that the loose ends of one set of fingers extend in the space between and toward the fixed ends of the other set, which enables the said fingers to act independently of each other upon an interior surface of equal or varying diameter in either direction.

In addition to the elasticity of the fingers I, I employ the force of the spiral spring *S*, which encircles the stem between the two sets of fingers and exerts a force in each direction against the disks *t*, as shown in Fig. 1. These disks are thus pressed against the under side of each set of fingers, near their junction with the stem, and are by this means spread farther asunder than they would be by their own elasticity. At the same time the fingers are prevented from bending short near the collar and thereby easily broken, any undue strain being borne by the disks *t*, supported by the elasticity of the spiral spring *S*.

Upon the stem *h* is fixed a suitable handle, *G*, by which the cleaner is revolved or otherwise operated when inserted in the chimney, the intention being to compress the elastic fingers with one hand sufficiently to make them enter the mouth of the chimney, and while holding the chimney in one hand to revolve and work the cleaner with the other hand, the elasticity of the fingers I causing them to conform to the contour of the chimney so effectually that the entire inner surface may be reached and cleaned.

It is obvious that the elastic fingers may be arranged, with the stem *h* and its handle, in a variety of ways suited to the different purposes for which an implement of this kind may be used. Among others, I have conceived the idea of uniting the loose ends of the two sets of fingers to each other in a hinge-joint, as

shown in Fig. 7, and making the collar *m* to slide upon the stem, whereby the said fingers may be expanded precisely like an umbrella, which arrangement will be found better adapted to cleaning the interior of globular-shaped lamp-shades, lantern-glasses, and the like than the arrangement first described.

I have also conceived the idea of arranging a third set of elastic fingers, attached to the collar *n*, with their loose ends extending upward in the same direction with those attached to the collar *m*, and bearing against an elastic ball or a similar device fixed upon a continuation of the stem *h*, to keep the said loose ends asunder, for the purpose of cleaning the upper (straight) portion of a lamp-chimney, while the other two sets of fingers are cleaning the swelling portion of the same chimney.

Modifications of these arrangements may be usefully applied to the cleaning of bottles and glassware generally.

Having thus described the construction of my improved lamp-chimney cleaner, what I claim therein as my invention, and desire to secure by Letters Patent, is—

1. A series of elastic wiping-fingers, each of which is fixed at one end and is loose at the other end, which by its own elasticity acts independently of the others and exerts a yielding pressure against the interior walls of a lamp-chimney when placed therein, substantially as herein shown and described, for the purpose specified.

2. The arrangement of two sets of such fingers so that the loose ends of one set of fingers extend toward the fixed ends of the other set of fingers, substantially as herein shown and described, for the purpose specified.

3. In combination with two sets of elastic fingers so arranged, two sliding disks arranged with a spiral spring or an equivalent force to press the said disks or other sliding piece toward the fixed ends of each set of fingers, substantially as shown and described, for the purpose specified.

MARTIN R. KENYON.
